UNITED STATES PATENT OFFICE.

ARTHUR BATES, OF LEICESTER, ENGLAND, ASSIGNOR TO UNITED SHOE MACHINERY COMPANY, OF PATERSON, NEW JERSEY, A CORPORATION OF NEW JERSEY.

SHOE-BEATING MACHINE

1,016,316.

Specification of Letters Patent.

Patented Feb. 6, 1912.

Application filed January 9, 1911. Serial No. 601,578.

To all whom it may concern:

Be it known that I, ARTHUR BATES, a subject of the King of England, residing at Leicester, in the county of Leicester, England, have invented certain Improvements in Shoe-Beating Machines, of which the following description, in connection with the accompanying drawings, is a specification, like reference characters on the drawings 10 indicating like parts in the several figures.

This invention relates to machines for beating or shaping shoes, and particularly to a machine of the type in which rotary beaters are employed for working the upper materials over a last bottom, and for shaping, compacting and smoothing the bottom of a lasted shoe to prepare it for the laying of the outsole.

An object of the invention is to provide 20 an improved machine in which the beating members have their working faces in position to work the upper materials inwardly from the two sides of a last bottom at the same time.

25 A characteristic of the machine, is the provision of a pair of beating members with their adjacent rubbing faces set edge to edge and inclined toward one another. By this arrangement an especially efficient treatment 30 is given to the shoe stock near the edge of the shoe bottom. Moreover the location of the working surfaces adjacent to one another provides for treating both sides of a shoe at once, and one of the rubbing members serves 35 to brace a shoe against lateral displacement by the action of the other member.

In accordance with the preferred embodiment of my invention herein shown and described, I provide a pair of rotary disks 40 arranged edge to edge, having rigid, ribbed or corrugated faces and arranged for movement about relatively stationary axes, which are preferably inclined toward one another to present in the same plane that portion of 45 their working surface which is intermediate between the axes of the two disks. The rubbing faces of these disks are preferably slightly convex. It should be understood however that convex is here used in its broad 50 sense to mean that the working surface of the disk slopes away or is inclined obliquely from the center to the periphery. It is equally within the contemplation of my in-

vention that the end face of the disk be beveled from the center outwardly to the 55 periphery in the form of a truncated cone, for example, or that the line of convexity of the end face be curved or an arc of a circle. In accordance with a very important further feature of my invention 60 the end faces or working surfaces of these disks are preferably formed with reversely inclined spiral ribs which extend outwardly from adjacent to the center a number of turns around their axes substantially to the 65 periphery. This disposition of the disks edge to edge for rotation about relatively fixed and inclined axes together within the spiral formation of the convex rubbing ribs operates to work the upper materials inwardly from 70 the side of a last bottom with a screwing movement. The pressure of the tool upon the work is localized at any given time upon a comparatively small high pressure area. Moreover the high pressure areas are constantly shifting or traveling inwardly from 75 the side of the last bottom toward the center, and in consequence the shoe stock is wormed inwardly, for, as the loci of high pressure are constantly shifting, some part of the 80 tool is always contacting with the work to drag it toward the center and away from the edge of the shoe. Furthermore, the spiral formation on the end faces of the disks is so arranged as to effect intermittent 85 depressions of a shoe having a rounded bottom as the outer ends of the ribs pass over it. Accordingly, means may conveniently be provided for raising the shoe after each 90 such depression thereby initiating with impact the engagement of the shoe with a new portion of the ribs.

These and other features of the invention will appear from the following description of an illustrative embodiment thereof read 95 in connection with the accompanying drawings, and will be definitely pointed out in the appended claims.

Referring to the drawings: Figure 1 is an elevation of the machine. Fig. 2 is a plan view of the disks. Fig. 3 is a section on the line 2-2 of Fig. 2.

The machine comprises a suitable frame in which is arranged a bearing 2 for supporting a shaft 4. The shaft 4 which is 105 driven by a pulley 3 is provided with a bev-

eled gear connection with a shaft 6 for driving the shaft 6. The two shafts 4 and 6 carry securely fixed thereto, beating disks 8 and 10, these disks 8 and 10 being provided on their ends with beveled or convex working faces which, as shown are formed with long spiral ribs 12 and 14; each spiral starting from a point 16 adjacent to the center of the disk and extending outwardly a number of times around the axis substantially to the periphery of the end face. These spirals 12 and 14 are oppositely wound or reversely inclined with relation to each other, (Fig. 2). The convolutions of the spirals 12 and 15 14 are separated each from the other by a very substantial space, as clearly shown in Fig. 2. This formation of the convex rubbing ribs in substantially spaced spiral convolutions operates to effect intermittent 20 pressions of the rounded bottom shoe operated on, as the outer ends 24, 26 (Fig. 2) of the ribs 12, 14 pass over it. This results in a bumping movement of the shoe as it engages a new part of the rib. To raise the 25 shoe to contact with the ribs after each such depression any suitable means may be employed, such for example, as is illustrated in Fig. 1 in which the shoe is shown with its last connected to a spindle 18 in a shoe 30 supporting jack 20; the jack being shown as yieldably supported by a spring 22 which normally tends to raise the shoe in elevated position and which therefore, whenever in the rotation of the beaters, the outer ends 24, 35 26 of the ribs 12, 14 pass over the shoe, operates to immediately elevate the shoe into operative engagement with new parts of the ribs, accomplishing this positioning of the shoe without any violent bumping or 40 bounding.

It will be noticed that the working surfaces of the disks are edge to edge or adjacent to one another (Fig. 2). Moreover, the axes of the disks 8 and 10, namely, the shafts 45 4 and 6 are, as shown in Fig. 1, preferably inclined one toward the other and are stationary relatively to each other. Preferably, the inclination of the shafts 4 and 6 is such as to present in the same plane that 50 portion of the working surface of each disk that is for the time being intermediate between the axes of the disks as plainly shown in Fig. 1. This disposition of the disks together with the spiral formation of the convex ribs, (Figs. 2 and 3) before described, adapts the disks for engaging simultaneously the two opposite sides of the shoe bottom with a peculiar screw-like movement 55 whereby the stock is at the same time worked inwardly from the two sides, and each tool is made to exert a maximum pressure at first on the edge of the shoe bottom and then in succession on points successively nearer the center producing in effect, 60 65 small high pressure areas, as for example

at 28 (Fig. 3) continually shifting inwardly. As a result, without injury to the stock, the stock is more thoroughly, evenly, and smoothly worked toward the center and away from the edges.

In operation, the shoe is successively treated at the heel seat and then if desired, along the shank, forepart and toe portions, the operator either holding the shoe up to the machine, and shifting it longitudinally thereof by hand or, if a construction such as is shown in Fig. 1 be employed, the supporting jack 20 may be arranged to slide back and forth lengthwise of the shoe.

Having now explained my invention and described in detail one illustrative embodiment thereof, what I claim as new and desire to secure by Letters Patent of the United States is:

1. A shoe shaping machine, having, in combination, two rotary disks, arranged edge to edge, and provided on their ends with reversely inclined spiral ribs extending one or more times around their axes.

2. A shoe shaping machine, having, in combination, a pair of disks arranged edge to edge for movement about relatively stationary axes that are inclined toward one another, and having on their ends beveled working faces comprising reversely inclined spiral ribs extending one or more times around their axes.

3. A shoe shaping machine, having, in combination, a pair of disks provided on their ends with convex working faces, and arranged to turn on axes that are inclined toward one another to present in the same plane that portion of the working surface which is intermediate between the axes of the two disks.

4. A shoe shaping machine, having, in combination, a pair of disks having on their end faces rigid beating surfaces, rotated by means of a beveled gear connection about relatively stationary axes that are inclined toward one another for presenting in the same plane that portion of the working surface which is intermediate between the axes of the two disks, each of the said beating surfaces comprising a spiral rib extending from adjacent to the center a plurality of times around the axis substantially to the periphery.

5. A shoe shaping machine, having, in combination, disks rotating about relatively stationary axes, and having on their ends reversely inclined spiral ribs extending one or more times around their axes to work the upper materials inwardly from the two sides of a last bottom at the same time, one rib serving to brace the shoe against lateral displacement by the action of the other rib.

6. In a machine of the class described, a disk beater having a work beating end face inclined from its center toward its periph-

- ery and formed with a spiral work rubbing rib extending from adjacent to the center a plurality of times around its axis substantially to the periphery.
7. A shoe beating machine of the class described, having, in combination, a pair of disks having beveled end faces which are their working surfaces and arranged edge to edge for rotating about axes inclined to present in the same plane that portion of the working surface of each disk that is intermediate between their axes, and having on said working surfaces reversely inclined spiral ribs for simultaneously screwing the upper materials inwardly from the two sides of a last bottom.
8. A shoe beating machine of the class described, having, in combination, a pair of disks having beveled end-faces which are the working surfaces, said disks being arranged edge to edge and rotating on axes inclined to present in the same plane that portion of each working surface that is for the time being intermediate between the axes of the disks, each disk having a long spiral rib extending one or more times around its axis and adapted for treating the shoe bottom with a small, constantly shifting high pressure area.
9. A shoe beating machine, having, in combination, a pair of disks having beveled end faces and arranged edge to edge to rotate on axes inclined to present in the same plane that portion of the working surface of the disks that is intermediate between their axes and formed on said end faces reversely inclined spiral ribs arranged to effect intermittent depression of a rounded bottom shoe, substantially as described, and means for raising the shoe after the outer ends of the ribs pass over it thereby causing engage-
- ment by impact of the shoe against a new portion of said ribs.
10. A shoe beating machine, having, in combination, a pair of rotating disks arranged edge to edge to present adjacent portions of their end faces for treating simultaneously the opposite sides of a shoe bottom, and having formed on said end faces reversely inclined spiral ribs, each extending one or more times around the axis of its disk and having its convolutions separated by a substantial space, whereby to produce a pressure area moving inwardly on the shoe bottom as the spiral turns and effect intermittent depression substantially as described of a shoe having a rounded bottom, and yielding means arranged to force the shoe by impact against the rib after each depression.
11. In a machine of the class described, a disk beater having a work beating end face inclined from its center toward its periphery and formed with a spiral work rubbing rib extending from adjacent to the center a plurality of times around its axis substantially to the periphery, and means to assist the operator in presenting a shoe with its bottom face to be treated substantially parallel with the adjacent inclined portion of said face whereby the shoe bottom is treated by a small portion of a rib which is convex relatively to the plane of the shoe bottom and is constantly shifting from the edge of the shoe inwardly for the purpose described.

In testimony whereof I have signed my name to this specification in the presence of two subscribing witnesses.

Corrections in Letters Patent No. 1,016,316.

It is hereby certified that in Letters Patent No. 1,016,316, granted February 6, 1912, upon the application of Arthur Bates, of Leicester, England, for an improvement in "Shoe-Beating Machines," errors appear in the printed specification requiring correction as follows: Page 1, line 66, for the word "periphey" read *periphery*; same page, line 68, for the word "within" read *with*; and that the said Letters Patent should be read with these corrections therein that the same may conform to the records of the case in the Patent Office.

Signed and sealed this 26th day of March, A. D., 1912.

Acting Commissioner of Patents.

- ery and formed with a spiral work rubbing rib extending from adjacent to the center a plurality of times around its axis substantially to the periphery.
7. A shoe beating machine of the class described, having, in combination, a pair of disks having beveled end faces which are their working surfaces and arranged edge to edge for rotating about axes inclined to present in the same plane that portion of the working surface of each disk that is intermediate between their axes, and having on said working surfaces reversely inclined spiral ribs for simultaneously screwing the upper materials inwardly from the two sides of a last bottom.
8. A shoe beating machine of the class described, having, in combination, a pair of disks having beveled end-faces which are the working surfaces, said disks being arranged edge to edge and rotating on axes inclined to present in the same plane that portion of each working surface that is for the time being intermediate between the axes of the disks, each disk having a long spiral rib extending one or more times around its axis and adapted for treating the shoe bottom with a small, constantly shifting high pressure area.
9. A shoe beating machine, having, in combination, a pair of disks having beveled end faces and arranged edge to edge to rotate on axes inclined to present in the same plane that portion of the working surface of the disks that is intermediate between their axes and formed on said end faces reversely inclined spiral ribs arranged to effect intermittent depression of a rounded bottom shoe, substantially as described, and means for raising the shoe after the outer ends of the ribs pass over it thereby causing engage-
- ment by impact of the shoe against a new portion of said ribs.
10. A shoe beating machine, having, in combination, a pair of rotating disks arranged edge to edge to present adjacent portions of their end faces for treating simultaneously the opposite sides of a shoe bottom, and having formed on said end faces reversely inclined spiral ribs, each extending one or more times around the axis of its disk and having its convolutions separated by a substantial space, whereby to produce a pressure area moving inwardly on the shoe bottom as the spiral turns and effect intermittent depression substantially as described of a shoe having a rounded bottom, and yielding means arranged to force the shoe by impact against the rib after each depression.
11. In a machine of the class described, a disk beater having a work beating end face inclined from its center toward its periphery and formed with a spiral work rubbing rib extending from adjacent to the center a plurality of times around its axis substantially to the periphery, and means to assist the operator in presenting a shoe with its bottom face to be treated substantially parallel with the adjacent inclined portion of said face whereby the shoe bottom is treated by a small portion of a rib which is convex relatively to the plane of the shoe bottom and is constantly shifting from the edge of the shoe inwardly for the purpose described.

In testimony whereof I have signed my name to this specification in the presence of two subscribing witnesses.
